UNITED STATES PATENT OFFICE.

OSCAR HIDALGO, OF NEW YORK, N. Y.

DUPLICATOR.

Application filed July 21, 1921. Serial No. 486,540.

To all whom it may concern:

Be it known that I, OSCAR HIDALGO, a citizen of the Republic of Chile, and a resident of New York, county and State of New York, have invented certain new and useful Improvements in Duplicators, of which the following is a specification.

The present invention relates to duplicators of the class described and shown in the 10 co-pending application filed May 28th, 1921, Serial No. 473,348, and more particularly to accessories thereof.

A duplicator of this class has a curved presser plate carrying on its outer face an 15 ink pad and stencil sheet. The ink pad is attached in position by rigid members or rods of the ink pad engaging sockets provided at the ends of the presser plate. The printing operation is performed by swinging 20 the curved duplicator from one end to the other over the face of the sheet like the well known press blotters, whereby the matter written or printed on the stencil sheet is impressed on the sheet.

25 The principal object of this invention is to provide an operating base with means to hold the sheets of a pile in alinement and equip the base with means whereby the duplicator may for each operation be quickly 30 properly positioned over the pile so as to produce uniform neat and clean copies.

Another object is to make said means adjustable to conform with various sizes of sheets and various arrangements of the 35 copied matter on the sheets.

With these and other objects in view my invention consists in the novel construction, arrangement and combination of parts as will be hereinafter more fully described and 40 defined in the appended claims.

In the accompanying drawing Fig. 1 is a top plan view of the operating base; Fig. 2 is an enlarged section on line 2—2 of Fig. 1; Fig. 3 is a top plan view of a modified 45 construction of the base; Fig. 4 is an enlarged section on line 4—4 of Fig. 3; Fig. 5 is an enlarged section on line 5—5 of Fig. 3 and Fig. 6 is an enlarged section on line 6—6 of Fig. 3.

50 In the drawing 10 denotes a board of wood or other suitable material substantially of rectangular shape designed to be larger both in length and width than the duplicator and serving as an operating or printing base. The board 10 is equipped

with members 12, 12' projecting from its upper face and adapted to serve as marginal stops or guides for the sheets adapted to be arranged in a pile thereon, whereby the sheets will be held in proper alinement with 60 one another during the printing operation.

The members 12, of which there may be one or more, are arranged near the end of the board, which relative to the direction of 65 operation is the front end, and one or more of the members 12' are located near one side of the board. These members are arranged

outside of the space adapted to be occupied by the stack of sheets and may be in form of bolts or the like. The printing being effected by rolling or swinging the duplicator from one end to the other, it is necessary, in order to prevent the duplicator from striking the front member 12 when its front 70 end is lowered and overlaps the front ends 75 of the sheets, to make said member 12 yielding in vertical direction. To this end the bolt 12 is movably borne in a bore 10' extending throughout the thickness of the

board and which is somewhat enlarged at its 80 bottom to form a socket for a member 13 to which one end of a spring 14 is attached. The bolt 12 at its inner end may be formed with a flange 12^a adapted to slidably bear on the walls of the enlarged portion of the bore 85 10'.

The space between the inner face of the flange 12^a and that of the member 13 is sufficiently large to permit the bolt 12 to be completely depressed so that its outer end 90 will be flush with or below the upper face of 95 the board.

In order to facilitate the positioning of the duplicator prior to the printing operation so that the matter to be copied on the sheets will run straight and appear on the sheets at the desired place, I provide the following means:

The cylindrically curved presser plate of the duplicator *a* which is indicated in dotted lines in Fig. 2, is provided with lateral projections *b* which in the co-pending application above referred to are formed by the ends of rigid members or rods of the ink pad, but which, of course, may be independent of the ink pad and fixed to any suitable place of the longitudinal walls of the presser plate.

Extending longitudinally near the side edges of the board and outside of the space to be occupied by the sheets are grooves 10^a 110

which on top are covered by metal strips 15 countersunk in the board as at 10³ and fixed to the board by screws 16 or the like. These strips are formed with longitudinal slots 15' constituting guides for members 17. These members are in form of elbow pieces, the horizontal parts of which slidably bear on the strips 15 and the vertical parts of which are directed towards one another and are formed with vertical notches 17'. The horizontal piece of each member is provided with a bore 17² through which extends a bolt 18 projecting through the slot 15' into the groove 10² and formed on its inner end with a head 18'. On the outer screw threaded ends of the bolts works thumb nuts 19 serving for the tightening of the members 17 in adjusted position. The notches 17' of the elbow pieces 17 serve as sockets for the lateral projections *b* of the duplicator so that the latter upon its engagement with the said corner pieces may be properly positioned prior to the printing operation. According to the length of the sheets used or the arrangement of the printing matter on the sheets the two corner pieces can be adjusted longitudinally to be in juxtaposition and at the desired distance relative to the sheets. For facilitating correct adjustment of the two corner pieces, to prevent printing on a bias and permit the arrangement of the matter copied within the desired space, scales 20 may be provided alongside the strips 15 as shown in Fig. 1.

In the present example the projections *b* are assumed to be arranged at one end of the duplicator. In such case the projections will engage the notches 17' of the elbow pieces 17 only at the beginning of the printing operation, that is to say, at the moment the duplicator is placed with its rear end onto the sheet while its forward end is raised. When the duplicator is rolled over the face of the sheet the rear or lowered end thereof will rise and the projections *b* will be lifted from the notches 17'. When, however, the projections are arranged centrally of the duplicator the pieces 17 may be so adjusted that the projections will remain in the sockets 17' during each printing period.

By the provision of the guide members 17 for the duplicator the printing of numerous copies in the shortest possible time is rendered possible, and uniform clean and neat copies can be produced.

In order to enable the use of sheets of various sizes the guides 12 and 12' may be made adjustable longitudinally and transversely respectively. Such construction is shown in the modifications of Figs. 3 and 5. Here the board 21 is provided at one end, preferably centrally, with a longitudinal groove 21', the bottom of which is formed by a removable plate 22 on which is

slidably mounted a disk or plate 23 having a projecting pin 24. The guide bolt 25 that corresponds to bolt 12 of the construction shown in Fig. 1 is formed with a longitudinal central groove 25' whereby the bolt 25 is movably mounted on the pin 24. A spring 26 attached to the disk or plate 23 with one end and bearing at its other end against the flange 25² of the bolt 25 tends to hold the latter projected outwardly from the groove 21'. This bolt 25 is thus yielding vertically and also capable of adjustment longitudinally. The board 21 is also provided with transversely extending parallel grooves 27 preferably of dove-tailed cross section, as indicated by dotted lines in Fig. 3, to slidably bear correspondingly shaped strips 28 of metal or wood. Said strips are at their outer faces flush with the board and carry at opposite ends each a bolt 29 which projects upwardly and serves as stop or guide for the sheets. By moving said strips or bars in opposite directions, the bolts 29 may be brought closer or farther away relative to one another according to the size of sheets used.

The bolts 29 may also be made yielding vertically like the bolt 25 or 12, to prevent the duplicator from striking them when the sheets used are narrower than the duplicator. To this end the pins 29 are movably borne in bores 28' of the strip 28 and are supported on suitable springs 30 fixed to the inner face of each strip.

The elbow pieces 31 for the engagement of the duplicator as shown in this modification may be attached to blocks 32 of dove-tailed cross section slidably borne in longitudinal correspondingly shaped grooves 33 provided in the board 21. The tightening of the blocks 32 in adjusted position may be effected by set screws 34 (see Figs. 3 and 6).

What I claim is:—

1. An operating board for a duplicator having lateral projections, said board having longitudinal marginal guide grooves, members adjustably mounted in said guide grooves and constituting sockets for said lateral projections and means for tightening said members in adjusted position.

2. An operating board for a duplicator having lateral projections, said board having longitudinal marginal guide grooves and members adjustably borne in said grooves and formed with projecting notched portions serving as sockets to engage said projections of the duplicator and means for tightening said members in adjusted position.

3. An operating board for a duplicator having lateral projections, said board having longitudinal marginal guide grooves, slotted plates or strips covering said grooves and fixed to said board, members adjustably borne in said grooves and formed with pro-

jecting notched portions adapted to form opposite ends of the slides, said member and sockets to engage said projections and means 10 for tightening said members to said plates sheets. in adjusted position.

5. 4. An operating board for duplicators, said board having a longitudinally adjustable resilient member and transversely extending slides having vertical projections at

OSCAR HIDALGO.
